APPARATUS FOR SEPARATING IMPURITIES FROM GAS

Filed March 18, 1921

UNITED STATES PATENT OFFICE.

JOHN R. FREEMAN, OF PROVIDENCE, RHODE ISLAND.

APPARATUS FOR SEPARATING IMPURITIES FROM GAS.

Application filed March 18, 1921. Serial No. 453,336.

This invention is an apparatus for the separation of impurities from producer or other gas.

In the process of manufacturing producer gas for fuel or other purposes, the gas as it is produced by distillation of bituminous coal in an appropriate retort, comes off filled with minute particles of tarry and oily vapor. These particles are so minute, and so completely permeate the gas that it has heretofore been difficult to separate them, and thereby obtain a gas sufficiently clean and free from particles of tar, ashes, coke, etc., to be used in gas engines, or for fuel in the modern elaborate bi-product coke and gas ovens, without clogging their passages.

One of the objects of the invention is to provide an apparatus of the character mentioned, by means of which the suspended impurities may be eliminated from the gas, by the aid of centrifugal action. A further object is to provide means for conveniently collecting the separated impurities, and conducting them to places where they may be stored, or suitably disposed of. A further object is to provide a centrifugal device, having means whereby an electrical discharge may be utilized to aid it in the process of separation.

The invention will be hereinafter fully set forth and particularly pointed out in the claims.

In the accompanying drawings:—

Figure 1 is a longitudinal sectional view of a gas conduit with the invention applied thereto. Figure 2 is a detail side elevation illustrating the rotary member of the centrifugal device. Figure 3 is a longitudinal section of a gas conduit with a modification of the invention applied thereto. Figure 4 is a transverse sectional view thereof.

Referring to Figures 1 and 2 of the drawing, 10 designates a casing provided with an inlet opening 11, and an outlet opening 12 surrounded by flanges 13. Said flanges are shaped to co-operate with the corresponding flanges on pipes 14 and 14^a, of a gas conduit to provide anti-friction bearings, for said casing, and with any convenient form of packing for preventing leakage of gas at the joint. Extending longitudinally through the pipes 14 and 14^a, and supported by suitable bearings, not shown, is a rotatable shaft 15, to which is keyed an impelling device 16, located within the casing 10 and at-

tached thereto so that casing and impelling device revolve together. Said impelling device is provided with a middle web or partition 17, having laterally extended vanes 18, on both sides thereof, extending to the contiguous walls of the casing. It will be noted that the periphery of the impelling device reaches nearly to the periphery of the casing 10, and that the latter is provided with outer openings 19. A device S is positioned to spray water into the inflowing gas.

In practice, the gas enters from pipe 14 and is discharged into pipe 14^a. In its course through the casing 10, it passes outwardly between the vanes 18, on the inlet side and inwardly between the vanes on the egress side. Said vanes may be either straight or curved, the edges of the vanes engaging the sides of the casing. After the gas enters the casing and while passing outwardly between the vanes 18, it is subjected to increasingly strong centrifugal pressure as it approaches the periphery of the casing, and, if the speed is sufficiently high, an extremely powerful force, much stronger than the force of gravity is exerted upon the particles of foreign matter contained within the gas, such as tar, watery vapor, fine particles of coke, cinder or ash. This force causes the said impurities to travel outwardly against the outer part of the casing 10, where they will form a film which, flowing in the direction of the gas, will be discharged through the orifices 19, while the gas itself passes onward around the central disk 17 and inwardly to the pipe 14^a. As the gas moves toward the center of the discharge side of the casing 10, the centrifugal pressure gradually becomes lower, until the gas finally escapes into the pipe 14^a, at a pressure and velocity but little less than those from which it entered from pipe 14.

The increase of pressure caused near the periphery of the revolving member will condense the gas, which will subsequently expand as it again approaches the center of revolution, so that this condensation and expansion will aid in the agglomeration and separation of the particles of foreign matter.

In the form of the invention illustrated in Figures 3 and 4, an impelling device of somewhat different form is employed, the revolving casing of Figure 1 being dispensed with. Referring to said figures, 25 designates a casing provided with an ink branch

26, and an outlet branch 27, both branches having flanges by means of which they may be secured to the pipes 27 of a gas main. In the chamber-like middle portion of the casing 25 is located a rotor 28, rigidly mounted upon a shaft 29, which is rotatably mounted in suitable bearings, and is driven in a manner not shown. Said impelling device is constructed with a middle web or partition 30, interposed between two sets of vanes 31. Surrounding the impelling device, are a plurality of disks 32, having perforations therein. The disks 32 are rigidly supported within the casing in suitable manner and are so disposed with respect to the impelling device that little gas can escape around the periphery of the impelling device but must mostly pass from the inlet branch 26 to the outlet branch 27 through the perforations of the plates.

It is a fact well-known to those experienced in the manufacture and purification of coal gas, that when gas containing tarry vapors and entrained fine particles of foreign substance, passes through an aperture with high velocity, and impinges against a plate, the particles of vapor and foreign substance will condense, forming a film, and are collected upon the surface of the plate.

In this case three plates are shown, but obviously a greater or less number might be used. The numerous apertures in these plates, through which the gas passes, are so disposed that the jets of gas impinge against solid portions of the plate. The films of tarry and other material thus collected, will drip by force of gravity downwardly, and will be collected in the chambers formed between the several perforated plates, from which chambers they may be drawn off through the pipes 33 into appropriate reservoirs. In its simple and ordinary form, the apparatus as described above will be connected within the circuit of the gas main leading from the retorts to the gas engine or bi-product oven, or other apparatus within which the purified gas is to be utilized.

The principles of this invention, while particularly set forth herein with respect to gases, are applicable to the purification of other fluids than gases. Any suspended particles occurring in fluids, whether the fluid be of the gaseous type or not, may be separated out by use of this invention.

Having thus explained the nature of the invention and described an operative manner of constructing and using the same, although without attempting to set forth all of the forms in which it may be made, or all of the forms of its use, what is claimed is:—

1. An apparatus for purifying gas comprising a casing with side and peripheral walls, a rotary shaft extending axially of the casing, a gas impelling device mounted to rotate with the shaft comprising a partition

perpendicular to the shaft and joining the shaft at each side in a smooth, tangential curve and lateral vanes extending from the partition and forming therewith compartments, an axial inlet opening through one side wall and an axial outlet opening through the other side wall, a continuously open discharge opening through the peripheral wall to permit the discharge of the heavy constituents of the gas separated therefrom by centrifugal action, inlet and outlet gas conduits surrounding the shaft and communicating with the casing at said axial openings, the curvature of the partition and the areas of the inlet and outlet conduits and openings being such as not materially to impede the constant flow of the gas through the casing determined by the area of the passageway therethrough.

2. An apparatus for purifying gas comprising a rotary casing with side and peripheral walls, a rotary shaft extending axially of the casing, a gas impelling device mounted to rotate with the shaft and casing comprising a partition perpendicular to the shaft and joining the shaft at each side in a smooth, tangential curve and lateral vanes extending from the partition to the side walls of the casing and forming therewith compartments, an axial inlet opening through one side wall and an axial outlet opening through the other side wall, a continuously open discharge opening through the peripheral wall to permit the discharge of the heavy constituents of the gas separated therefrom by centrifugal action, inlet and outlet gas conduits surrounding the shaft and communicating with the casing at said axial openings, the curvatures of the partition and the areas of the inlet and outlet conduits and openings being such as not materially to impede a constant flow of the gas through the casing determined by the area of the passageway therethrough.

3. An apparatus for purifying gas comprising a rotary casing with a side and peripheral wall having through said side wall an axial inlet opening for the gas to be purified and an axial outlet opening for the purified gas and through said peripheral wall a continuously open discharge opening to permit the discharge of the impurities, a rotary shaft extending axially through the casing, a gas impelling device fastened to the shaft to rotate therewith comprising a partition perpendicular to said shaft and joining the shaft in a smooth tangential curve of relatively large radius, and lateral vanes joining the partition and side walls of the casing to form compartments within the casing, inlet and outlet gas conduits surrounding said shaft and communicating with the casing at said axial openings, the radius of curvature of the partition and the size of the inlet and outlet conduits and openings being

such as not materially to impede a constant flow of the gas determined by the area of the passageway through the casing, whereby the impure gas will sweep into the compartments of the casing without depositing impurities in the inlet conduit to clog said conduit and be thrown by centrifugal force against the peripheral wall of the casing where the gas and impurities will separate and the purified gas may be easily passed out of the casing.

4. An apparatus for purifying gas comprising a rotary casing with a side and peripheral wall having through said side wall an axial inlet opening for the gas to be purified and an axial outlet opening for the purified gas and through said peripheral wall a continuously open discharge opening to permit the discharge of the impurities, a rotary shaft extending axially through the casing, a gas impelling device fastened to the shaft to rotate therewith comprising a partition perpendicular to said shaft and joining the shaft in a smooth tangential curve of relatively large radius, and lateral vanes joining the partition and side walls of the casing to form compartments within the casing, and a gas inlet conduit surrounding said shaft and communicating with the casing at one of said axial openings, the radius of curvature of the partition and the size of the inlet and outlet conduits and openings being such as not materially to impede a constant flow of the gas determined by the area of the passageway through the casing, whereby the impure gas will sweep through the axial opening into the compartments of the casing without depositing impurities in the inlet conduit to clog said conduit and be thrown by centrifugal force against the peripheral wall thereof where the gas and impurities will separate and thereafter the purified gas pass out of the casing through the axial outlet opening.

45 5. An apparatus for purifying a fluid comprising a casing with side and peripheral walls, a rotary shaft extending axially of the casing, a fluid impelling device mounted to rotate with the shaft comprising a parti-

tion perpendicular to the shaft and joining the shaft at each side in a smooth, tangential curve and lateral vanes extending from the partition and forming therewith compartments, an axial inlet opening through one side wall and an axial outlet opening through the other side wall, a continuously open discharge opening through the peripheral wall to permit the discharge of the heavy constituents of the fluid separated therefrom by centrifugal action, inlet and outlet fluid conduits surrounding the shaft and communicating with the casing at said axial openings, the curvature of the partition and the areas of the inlet and outlet conduits and openings being such as not materially to impede the constant flow of the fluid through the casing determined by the area of the passageway therethrough.

6. An apparatus for purifying a fluid comprising a rotary casing with side and peripheral walls, a rotary shaft extending axially of the casing, a fluid impelling device mounted to rotate with the shaft and casing comprising a partition perpendicular to the shaft and joining the shaft at each side in a smooth, tangential curve and lateral vanes extending from the partition to the side walls of the casing and forming therewith compartments, an axial inlet opening through one side wall and an axial outlet opening through the other side wall, a continuously open discharge opening through the peripheral wall to permit the discharge of the heavy constituents of the fluid separated therefrom by centrifugal action, inlet and outlet fluid conduits surrounding the shaft and communicating with the casing at said axial openings, the curvature of the partition and the areas of the inlet and outlet conduits and openings being such as not materially to impede a constant flow of the fluid through the casing determined by the area of the passageway therethrough.

In testimony whereof I hereunto affix my signature.

JOHN R. FREEMAN.
